UNITED STATES PATENT OFFICE.

AUGUSTUS O. BOURN, OF BRISTOL, RHODE ISLAND.

RUBBER BOOT.

SPECIFICATION forming part of Letters Patent No. 296,119, dated April 1, 1884.

Application filed January 4, 1884. (No model.)

To all whom it may concern:

Be it known that I, AUGUSTUS O. BOURN, of Bristol, in the county of Bristol and State of Rhode Island, have invented certain new and useful Improvements in Rubber Boots, &c.; and I do hereby declare that the following specification, taken in connection with the drawings furnished and forming a part of the same, is a clear, true, and complete description of my invention.

It is well known that the uppers of rubber boots and shoes as ordinarily constructed are liable to crack or break in crosswise lines adjacent to the ball of the foot, and also sometimes higher up on the instep. In proportion as said uppers are made thick and heavy said liability is decreased; but the desirable results in that respect are more than offset by the lack of flexibility in the upper, which renders the boot or shoe too stiff and clumsy for comfort to the wearer, and therefore it is desirable that the uppers have separated longitudinal portions of considerable thickness and intervening portions of lesser thickness, whereby, without unduly impairing its flexibility, the upper is rendered less liable to break laterally. Rubber boots and shoes have heretofore had their uppers longitudinally stiffened or strengthened at intervals by the application of longitudinal ribs to the inner surface of the upper, in which case a double service was performed by said ribs, in that they not only re-enforced the upper in longitudinal lines, but they also afforded intervening spaces, which served as ventilating-ducts between the foot or inner shoe of the wearer and the rubber boot or overshoe, as fully shown and described in the United States Letters Patent of Pease, No. 11,947, November 14, 1854. Rubber boots and shoes have also heretofore had separate longitudinal stiffeners applied side by side, but properly separated, and located between the usual lining of the upper and the usual sheet of vulcanizable gum compound which serves as the outer portion of the upper. A boot or shoe constructed in accordance with my invention has an upper which embodies a foundation fabric especially manufactured for my purposes, and having a smooth or plain faced back and a series of longitudinal integral ribs on its front side, and the usual sheet

of gum compound overlying the ribbed surface and vulcanized thereto. By the use of this fabric in light goods, no separate inside lining is needed and a boot or shoe with a smooth inner surface is obtained, and I obviate the expense in manufacture incident to the labor involved in the use of the separate longitudinal strips; and as the fabric used by me has its integral ribs always uniform in their dimensions, and as they are equally spaced, I am able to economically produce goods of uniform appearance, such as can only be produced by the expenditure of much extra care and labor when the separate longitudinal strips are employed.

To more particularly describe my invention, I will refer to the accompanying drawings, in which—

Figure 1 is a side view of a boot embodying my improvement. Fig. 2 is a lateral section of the same in front of the instep. Fig. 3 is a top view of the integrally-ribbed fabric employed as the foundation for the upper. Fig. 4 is a lateral section of said fabric.

The foundation fabric A may be woven or knit, as may be desired; but I prefer that it be a knitted fabric, because of its well-known elasticity. However said fabric may be manufactured, it must be provided with the integral longitudinal ribs a, in which the yarn is so massed as to render them much thicker and heavier than the fabric at the intervening spaces, b, thus radically differing from ordinary knit ribbed fabrics, which are practically uniform in thickness and have ribs which are alternately thrown to the front and to the rear of the fabric, and which, therefore, are ribbed on both sides, instead of being ribbed on the front side only, as shown in the drawings, 90 wherein the rear surface or back of the fabric c is smooth or plain.

When my uppers are made up on a last, the gum sheet d is so applied to the ribbed front surface that it is intimately united thereto, and so that the outer surface of the finished upper is longitudinally ribbed or corrugated in exact conformity with the fabric foundation, as clearly shown in Fig. 1.

When the preferred knitted fabric is employed, the finished boot has always a desirable fancy finish not before attained, in that

the spaces between the ribs present the appearance of having been ornamentally embossed in symmetrical wave lines; and, if desired, similar effects can obviously be produced with woven ribbed foundations.

It will be seen that in the manufacture of light goods I need use no lining, because the rear or inner surface of the foundation of the upper is smooth and sufficiently solid and compact to afford comfortable wearing contact. In heavier goods a lining can, however, be employed, if desired, without in any manner departing from my invention.

Having thus described my invention, I claim

as new and desire to secure by Letters Patent—

A rubber boot or shoe having a longitudinally-ribbed upper, composed of the usual sheet of vulcanizable gum compound, and a foundation fabric having integral longitudinal ribs on its front or outer surface and a plain or smooth inner surface or back, substantially as described.

AUGUSTUS O. BOURN.
